UNITED STATES PATENT OFFICE

149,574

DESIGN FOR A SUPPLY STAND FOR DENTAL GRINDING DISKS OR THE LIKE

Bernard B. Lowenstein, Forest Hills, N. Y.

Application March 6, 1946, Serial No. 127,134

Term of patent 14 years

(Cl. D80—9)

To all whom it may concern:

Be it known that I, Bernard B. Lowenstein, a citizen of the United States of America and residing at Forest Hills, county of Queens, State of New York, have invented a new, original, and ornamental Design for a Supply Stand for Dental Grinding Disks or the Like, of which the following is a specification, reference being made to the accompanying drawing, forming part thereof.

In the drawing:

Fig. 1 is a side-elevational view of a supply stand for dental grinding disks or the like, showing my new design;

Fig. 2 is a top plan view of the supply stand shown in Fig. 1;

Fig. 3 is a bottom plan view of the supply stand shown in Fig. 1.

I claim:

The ornamental design for a supply stand for dental grinding disks or the like, substantially as shown.

BERNARD B. LOWENSTEIN.
